SEWING MACHINE

Ralph A. Collins, White Plains, N. Y., assignor
to The Reece Button Hole Machine Company,
a corporation of Maine

Application June 28, 1939, Serial No. 281,548

15 Claims. (Cl. 112—74)

This invention relates to sewing machines of the type designed to sew a suitably positioned line of stitches around an area or opening such as a button hole, in the work, and more particularly to the work-clamping mechanism employed in such machines.

In button hole and similar sewing machines, the work-clamping mechanism usually comprises two clamps on the bed frame of the machine which are movable to and from each other and normally yieldingly urged toward each other. Each of these clamps consists of a work-supporting plate and a therewith cooperating clamping foot between which and the plate the work is clamped. After clamping the work, it is customary to spread the clamps, i. e., to move the plates with their respective clamping feet slightly away from each other in order to stretch or tension the work or to spread a button hole or other slit therein, as the case may be. Usually, the clamps are spread automatically into a predetermined maximum separated position after the machine has been started and before the actual sewing begins. It is also customary to provide stops for the work clamps, hereafter called "inner-limit" stops, to limit the approach of said work clamps toward each other. These inner limit stops are usually adjustable to and from each other in the direction of the movement of the clamps so that the latter, when moved from said stops outwardly into their maximum separated position, will traverse a distance which is just sufficient to effect any desired tension in, or spread of, any type of clamped material.

To spread the clamps into their maximum separated position, it is customary in machines of the type under consideration to employ a cam or spreader block which is mounted on a frame that carries the stitching instrumentalities, hereafter called the "stitch frame." Usually, the stitch frame also carries, without the operating region of the stitching instrumentalities, means for cutting a button hole or other slit in the stitching area of the clamped work. In order that both the cutting operation and the stitching operation may be performed during one uninterrupted operating cycle of the machine and while the work remains clamped, the stitch frame and the bed frame have relative movements in order to bring the stitching area of the clamped work on the bed frame from operative alignment with the cutting means, i. e., the cutting position, into operative alignment with the stitching instrumentalities, i. e., the stitching position, and vice

versa. As it is during the first of these relative movements in each operating cycle of the machine that the spreader block on the stitch frame engages suitable followers of the work clamps and performs its clamp-spreading function, and inasmuch as the work has to be already tensioned or spread at the beginning of the stitching operation, said first relative movement between the frames takes place from the cutting position into the stitching position. In addition to the before mentioned relative movements from cutting to stitching position, and vice versa, the stitch frame and the bed frame have further relative movements in two transverse directions for sewing around a button hole having an eye, for instance. In order that these further relative transverse movements may take place without interference from the spreader block, the latter is so constructed and arranged on the stitch frame that it will have completely cleared the followers of the work clamps on the bed frame at the end of the first relative movement in each working cycle between said frames from the cutting into the stitching position.

The present invention has for its primary object to provide novel means for holding the work clamps in their maximum separated position, against their normal tendency to yield toward each other, immediately after the spreader block has forced the work clamps into their maximum separated position and cleared the followers thereof and during the remaining operating cycle of the machine, and without interfering in the least with the requisite relative movements between the stitch frame and the bed frame during said remaining operating cycle.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

In the drawings:

50 Fig. 1 is a fragmentary side elevation, partly in section, of a sewing machine, including a work-clamping mechanism which embodies the present invention.

Fig. 2 is a fragmentary plan view of the machine with the stitch frame thereof partly broken

away for better illustration of the work-clamping mechanism underneath.

Fig. 3 is an enlarged section, taken substantially on the line 3—3 of Fig. 1 and showing the work-clamping mechanism in perspective.

Fig. 4 is an enlarged, fragmentary perspective view, partly in section, of certain cooperating elements of the work-clamping mechanism.

Fig. 5 is a longitudinal section through a modified construction of the work-clamping mechanism.

Fig. 6 is a fragmentary section, taken substantially on the line 6—6 of Fig. 5.

Referring to the drawings and particularly to Fig. 1 thereof, the present invention is shown as applied to a button hole sewing machine of a well-known type, comprising a stationary bed frame 15 which carries the work-clamping mechanism hereinafter described, a movable stitch frame or head 16 with the stitching mechanism, and mechanism on the stitch frame for cutting a button hole or the like. The stitch frame 16 is movable longitudinally over the bed frame 15 to bring the stitching and cutting mechanisms alternately into operative relationship with the work, and is also movable both longitudinally and laterally to position the stitches in accordance with the work to be performed, by means of feeding mechanism operated by a main cam 17 which is carried by the stitch frame 16 and rotated by any suitable power driven shaft (not shown). This feeding mechanism is well known in the art, being shown, for example, in the Patents to Reece No. 240,546, April 26, 1881, and No. 655,637, August 7, 1900, and many others, and requires no detail description herein.

The stitching mechanism comprises a needle 19 carried by a needle bar 20, and looper mechanism 14 which may be substantially as shown in the patent to Grip No. 1,905,854, April 25, 1933, said needle bar and said looper mechanism being carried by upper and lower turrets 21 and 22, respectively, which are rotated in unison at the proper time by gear segments (one being shown at 23 in Fig. 1) that are carried by a rock shaft 25, operated by the main cam 17 in a manner further described in the Reece patents above referred to. The lower turret 22 also carries a throat plate 26 through which the needle 19 passes in order to cooperate with the looper mechanism 14. The needle bar 20 is reciprocated vertically and vibrated laterally in its turret 21 in a manner substantially as shown and described in the patent to Reece No. 1,991,627, February 19, 1935. The looper mechanism 14 is operated in a manner substantially as shown and described in the patent to Grip above referred to and in the patent to Dunnell No. 1,935,083, November 14, 1933.

The cutting mechanism comprises upper and lower cooperating cutting elements 30 and 31, respectively, the former being carried by a lever or arm 32 which is operated at the proper time from the main cam 17 in a manner described more fully in the patent to Kiewicz No. 1,841,133, January 12, 1932.

It will be understood that in machines of this character suitable mechanism is provided whereby the machine, when started, will perform its operative cycle and then stop automatically, said cycle including, first, the clamping of the work by the work-clamping mechanism, then a movement of the stitch frame from the cutting position shown in Fig. 1, in which the cutting elements 30, 31 are adjacent the stitching region or area of the work, into the stitching position in 75

which the stitch-forming instrumentalities are adjacent said area, next, a stitching operation of the character determined by the design of the feed mechanism, then a return of the stitch frame 5 into the cutting position, and finally the release of the work from the work-clamping mechanism, said cycle also including a cutting operation which may be performed either before or after the stitching operation according to the design or adjustment of the machine.

Except as hereinafter pointed out, or as they enter into combination with the parts hereinafter described, the mechanisms above referred to specifically form no part of the present invention 15 and may be as shown and described in the patents referred to, or otherwise, as will be well understood by those skilled in the art.

The work-clamping mechanism in the present machine is in most respects like the one shown 20 and described in the copending application of Walter E. Nichols, Serial No. 272,780, filed May 10, 1939, which has resulted in Patent No. 2,201,449. Accordingly the work-clamping mechanism consists of two relatively movable 25 clamps 35 and 36, each comprising a work-receiving clamp plate 37 and a therewith cooperating clamping foot 38 which is carried by a slightly resilient arm 39, pivotally mounted at 40 on a block 41 which is adjustably mounted on the 30 plate 37 in the manner shown in Figs. 1 and 2. The clamp plates 37 are slidably supported on the upper machined surface 42 of the bed frame 15. Bordering the opposite sides of the machined bed surface 42 are raised ledges 43. Each clamp plate 35 37 carries a matrix 44, having its work-engaging surface 45 knurled or otherwise roughened the same as the sole of the therewith cooperating clamping foot 38, so that the clamped material therebetween may be more firmly gripped.

The clamp plates 37 are guided for linear movement at right angles to the longitudinal axis x—x (Fig. 2) of the line of stitching which is determined by the design of the feed mechanism. This is accomplished by providing linkages 47 between 45 the clamp plates 37 and the bed frame 15 in a manner fully described in the above co-pending application. As these linkage are identical in every respect, the following brief description of one linkage is deemed sufficient for an understanding of the operation of both linkages. Each linkage 47 consists of two levers or links 48 and 49 which are pivotally mounted at 50 and 51, respectively, on the underside of the bed frame 15 and floatingly pivotally connected with each other at 52. The front link 49 has a floating pivotal connection 53 with a slide 54 which is guided on the underside of the bed frame for movement at right angles to the longitudinal stitching axis x—x (Fig. 2) and longitudinally 60 adjustably connected at 55 with its respective clamp plate 37 near the front end thereof in a manner further described in the above-mentioned copending application. The rear link 48 has a floating pivotal connection 56 with said clamp plate 37 near the rear end thereof, said connection being afforded by a pin 56a on said rear link 48 and a longitudinal slot 56b in the underside of the clamp plate into which said pin projects. Movement of the slide 54 in either direction causes movement of the clamp plate 37 in either direction at right angles to the longitudinal stitching axis x—x, whereby said clamp plate is solely guided by its linkage 47, as will be readily understood.

Adapted to cooperate with the opposite, in-

clined ends 57 of the slides 54 of the linkages 47 are the inner-limit stop surfaces 58 of a non-rotatable wedge member 59, carried by a screw 60 which is rotatably but axially immovably mounted in the depending skirt 61 of the bed frame 15, all as described more fully in the above-mentioned co-pending application. Manual rotation of the screw 60 causes movement of the wedge member 59 in the direction of the stitching axis $x-x$ (Fig. 2) and, hence, adjustment of the inner-limit stop surfaces 58 relative to the slides 54. A tension spring 62, suitably anchored to the slides 54, normally urges said slides into engagement with the wedge member 59 and the clamp plates 37 toward each other, the latter 15 through intermediation of the linkages 47 as will be readily understood. Mounted on the raised ledges 43 of the bed frame 15 by means of screws 63 are two latch plates 64 for holding the clamp plates 37 down on their supporting surface 42.

Suitably mounted at 65 on the stitch frame 16 is a spreader block or cam 66 (Figs. 1 and 2) which is adapted to engage followers 67 on the underside of the clamp plates 37 and force the latter away from each other into a maximum separated position against the tendency of the spring-urged linkages 47 to force said clamp plates toward each other. This is accomplished after the material or work W has been clamped and while the stitch frame 16, and with it the spreader block 66, is moved by the feed mechanism from the cutting position shown in Figs. 1 and 2 into the stitching position, i. e., to the left as viewed in Figs. 1 and 2. The result is a tensioning or spreading of the clamped material to an extent which is determined by the adjustment of the wedge member 59, as will be readily understood. For previously stated reasons, the spreader block is so constructed and arranged on the stitch frame 16 that it will have completely cleared the followers 67 of the clamp plates 37 when the stitch frame arrives in the stitching position. To prevent, however, that the spring-urged linkages 47 yield the spread clamp plates 37 toward each other after the spreader block 66 has cleared the followers of said clamp plates, means hereinafter described hold the clamp plates in their maximum separated position until the end of the operating cycle.

After the machine has been started for an operating cycle and before the stitch frame 16 is moved from the cutting position to the stitching position, i. e., before the work clamps are spread into their maximum separated position by the spreader block 66, the clamping feet 38 are automatically lowered and pressed against the work W on the clamp plates 37 by mechanism which is shown and described in detail in the patent to Kiewicz, No. 1,841,133, January 12, 1932. To this end, the rocker 80, which is pivotally mounted at 81 on the underside of the bed frame 15, has two spaced arms 82 (Figs. 1 and 2), each terminating in a roller-shaped end 83 which is received in the forked end 84 of an extension 85 of a clamp arm 39. The rocker 80 carries a depending bracket 86 which pivotally supports at 87 one end of a toggle member 88, the other end thereof being pivotally connected at 89 with one end of a cooperating toggle member 90. The other end of the toggle member 90 is pivotally mounted at 91 on the bed frame 15 and has an extension 92 formed as a handle for manual operation of the toggle members 88 and 90, if desired. A tension spring 93, anchored with one

end on the bracket 86 and with the other end on the bed frame 15, normally tends to collapse the toggle members 88, 90 and to rotate the rocker 80 clockwise as viewed in Fig. 1 and thereby lift the clamping feet 38 out of engagement with the work W on the clamp plates 37.

In the dotted-line position of the toggle members 88, 90 shown in Fig. 1, i. e., their home position, the clamping feet 38 are in the illustrated 10 raised, dotted line position. For the purpose of automatically lowering the clamping feet 38 into firm engagement with the work W on the clamp plates 37, the lower toggle member 88 is provided with a laterally extending arm 95 with which a lever 96 is adapted to cooperate. This lever 96, which is suitably pivoted on the bed frame 15 and shown in dotted lines in its home position (Fig. 1), is provided with a follower 97 which is normally urged into cooperative engagement with the main cam 17 of the machine by a suitably anchored tension spring 98. The main cam 17 is provided with a cam lobe 99 which is adapted to depress lever 96 from the dotted line position into the full line position shown in Fig. 1 shortly after the machine has been started. While the lever 96 is thus being depressed, the same engages and rocks arm 95 into the full line position shown in Fig. 1, with the result that the toggle members 88 and 90 are rocked into their full line position (Fig. 1) and the clamping feet 38 are lowered 20 into their full line position (Fig. 1) in which they are in clamping engagement with the work W. The lever 96 disengages from the arm 95 and is yielded into its dotted line position (Fig. 1) immediately after the crest 99a of the cam lobe 99 clears the follower 97. Provisions are also made to prevent the free collapse of the toggle members 88, 90 in their full line position (Fig. 1). To this end, the toggle members 88, 90 are provided with shoulders 100 and 101, respectively, which engage each other when said toggle members assume the full line position in Fig. 1 in which their pivot connection 89 is slightly to the left of a straight line passing through their other pivot 25 connections 87 and 91 with the bracket 86 and the bed frame 15, respectively. Thus, the shoulders 100 and 101, in conjunction with the spring 93, effectively prevent the collapse of the toggle members 88, 90 in either direction, and permit their collapse into the dotted line position in 30 Fig. 1 only after the toggle members have been rocked against the tension of the spring 93 from the full line position into a position in which their pivot connection 89 has moved to the right 35 as viewed in Fig. 1 beyond alignment with a straight line passing through their other pivot connections 87 and 91 with the bracket 86 and the bed frame 15, respectively. The toggle members 88, 90 are automatically collapsed at the end 40 of an operating cycle of the machine in a manner fully shown and described in the above mentioned Kiewicz Patent No. 1,841,133, thereby releasing the work W from the clamps for removal therefrom.

Provisions are made to hold the clamp plates 37 in their maximum separated position after the spreader block 66 has cleared the followers 67 of said clamp plates during the first movement of the stitch frame in an operating cycle of the machine from the cutting to the stitching position. To this end, the roller-shaped ends 83 of the rocker 80, as well as the forked ends 84 of the clamp arms 39 are inclined to the plane of the clamp plates 37 in the manner shown in 45 Figs. 3 and 4. After the arms 39 with their

clamping feet 38 have been rocked into clamping engagement with the work W on the clamp plates 37 in their inner-limit position (Fig. 3), the latter are forced into their maximum separated position by the spreader block 66, whereby the forked ends 84 of the clamp arms 39 slide outwardly on the roller-shaped ends 83 of the rocker 80, as will be readily understood. When the spreader block 66 clears the followers 67 of the clamp plates 37, the forked clamp arm ends 84 become immediately wedged against the roller-shaped rocker ends 83 with such force that said clamp and, hence, the clamps are firmly held in their maximum separated position in spite of any vibration of the machine and despite the tendency of the spring-urged linkages 47 to return the clamps to their inner-limit position. This appears clearly from Fig. 4 wherein the indicated pull-down force F exerted by the rocker 80 keeps the opposite, inclined surfaces 110 and 111 of a roller-shaped rocker end 83 and a forked clamp arm end 84, respectively, in firm engagement with each other, thereby preventing the yielding of said clamp arm and its respective clamp plate from the maximum separated position shown in full lines into the inner-limit position shown in dotted lines. The inclination of the roller-shaped rocker ends 83 and of the therewith cooperating clamp arm forks 84, the resiliency of the clamp arms 39 and the pull-down force F of the rocker 80 are, of course, so related that the work W remains firmly clamped on the plates 37 even after said clamp arm forks 84 have been moved on and relative to their respective roller-shaped, inclined rocker ends 83 outwardly into the maximum separated position. The clamp arms 39 and their respective clamp plates 37 are evidently held in the maximum separated position by the roller-shaped rocker ends 83 and the therewith cooperating clamp arm forks 84 until the work is automatically released from the clamps at the end of an operating cycle of the machine, whereupon the spring-urged linkages 47 will return the clamp plates 37 to their inner-limit position.

Figs. 5 and 6 disclose a modified work-clamping mechanism wherein the clamp arms 39 are rotatably and axially slidably mounted on pivots 115 which are slightly inclined to the plane of the clamp plates 37 and lie in a plane which extends at right angles to said plane of the clamp plates and parallel to the direction of movement of the latter. Each pivot 115 is carried by the spaced arms 116 of a block 117 which is mounted on the bed frame 15, while the hub 118 of each clamp arm 39 is straddled by the spaced forked arms 119 of a bracket 120 which is mounted on a clamp plate 37 so that said clamp arm is axially movable with its clamp plate 37 relative to its pivot 115. To provide for uniform engagement of the end surfaces 122 of each clamp arm hub 118 with the surfaces 123 of the straddling arms 119 of a bracket 120 in any angular position of the clamp arm, the surfaces 122 and 123 lie in planes which are parallel to the rocking plane R—R (Fig. 6) of said clamp arm. The fork legs 84a of the clamp arms 39 may be disposed as shown in Figs. 5 and 6 and the fork-engaging ends 83a of the rocker 80 may be of the shape shown in section in Fig. 6 or any other suitable cross-sectional shape. It is evident that, when the rocker ends 83a maintain the clamp arms in clamping engagement with the work, said rocker ends and the inclined pivots 115 cooperate to wedge said clamp arms against yielding from their maximum separated position into their

inner-limit position in the direction of arrow 125 (Fig. 6).

It is also conceivable to mount the clamp arms 39 axially immovably on their pivots 115 (Fig. 6) and to axially slidably support the ends of said pivots 115 in the spaced arms 116 of the blocks 117.

I claim:

1. In a sewing machine, the combination of a work-supporting surface; a pivot; a thereon pivoted, axially movable member rockable into and out of clamping engagement with the supported work; and an element engaging said member and operable to force the latter in any axial position

15 into clamping engagement with the supported work, at least one of the engaged surfaces of said member and element being inclined to the pivot axis whereby said member is wedged against axial movement in one direction while said element maintains the member in clamping engagement with the work.

2. The combination in a sewing machine as set forth in claim 1, wherein said element is so movable and coordinated with said member as to 25 rock the latter in any axial position into clamping engagement with the work.

3. The combination in a sewing machine as set forth in claim 1, wherein said element is so movable and coordinated with said member as to rock the latter in any axial position out of clamping engagement with the work.

4. The combination in a sewing machine as set forth in claim 1, wherein said element is so movable and coordinated with said member as to 35 rock the latter in any axial position into and out of clamping engagement with the work.

5. In a sewing machine, the combination of a work-supporting surface; a pivot element; a thereon pivoted, axially movable clamp having a fork; and a member movable in a plane at right angles to said surface and having a finger element traversing said fork in any axial clamp position for rocking said clamp into and out of clamping engagement with the supported work, said elements being so inclined to each other that the clamp is wedged against axial movement in one direction while said finger element maintains said clamp in clamping engagement with the work.

50 6. The combination in a sewing machine as set forth in claim 5, wherein said pivot element is parallel to said surface and said finger element is inclined to said pivot element.

7. The combination in a sewing machine as set forth in claim 5, wherein said pivot element is axially immovable and inclined to said surface and said finger element is axially parallel to said surface.

8. In a sewing machine, the combination of a work-supporting surface; a clamp member closable against the supported work and movable in a predetermined path parallel to said surface; and a member immovable in the direction of said path and operable to engage said clamp member in any position on said path and maintain it in clamping engagement with the supported work at least one of the engaged surfaces of said members being so inclined to said supporting surface that said clamp member is wedged against movement in one direction of said path while clamping the work.

9. In a sewing machine, the combination of a work-supporting surface; a pivotally mounted clamp bodily movable in opposite directions in a plane parallel to said surface; and an element

immovable in said opposite directions and engaging said clamp and operable to force said clamp in any bodily position into clamping engagement with the supported work, at least one of the engaged surfaces of said clamp and element being so inclined to said supporting surface that said clamp is wedged against bodily movement in one of said opposite directions while said element maintains the clamp in clamping engagement with the work.

10. In a sewing machine, the combination of a work-supporting surface; an axially movable clamp pivotally mounted about an axis parallel to said surface; and an element engaging the clamp and being movable in a plane substantially parallel to the rocking plane of said clamp for rocking the latter in any axial position into and maintaining it in clamping engagement with the supported work at least one of the engaged surfaces of said element and clamp being so inclined to said supporting surface that said clamp is wedged in any axial position against axial movement in one direction while said element maintains said clamp in clamping engagement with the work.

11. The combination in a sewing machine as set forth in claim 10, wherein said element has a finger, said clamp has a fork of which the spaced legs extend longitudinally at right angles to the pivot axis of the clamp and lie in parallel planes inclined to said pivot axis, and said legs are so wide as to receive said finger in any axial clamp position.

12. In a sewing machine, the combination of a work clamp including a work plate movable in opposite directions in the plane of said plate, and a member pivoted on said plate; and an element engaging said member and being movable in a direction other than said opposite directions for rocking said member into and maintaining it in any plate position in clamping engagement with the work on said plate, at least one of the engaged surfaces of said member and element being so inclined to said plate that the latter is wedged against movement in one of said opposite directions while said member is in clamping engagement with the work.

13. In a sewing machine, the combination of a work supporting surface; two pivotally mounted clamps bodily movable to and from each other in a plane substantially parallel to said surface; and an element engaging said clamps and adapted to simultaneously rock said clamps in any bodily position into and maintain them in clamping engagement with the supported work at least one of the engaged surfaces of each clamp and said element being so inclined to said supporting surface that each clamp is wedged in any bodily position against movement in one of the opposite directions of its to and fro movement while said element maintains the clamps in clamping engagement with the work.
14. In a sewing machine, the combination of a work clamp including two work plates movable parallel to their surfaces to and from each other, and two members pivoted on said plates; and an element engaging said members and adapted to simultaneously rock the latter into and maintain them in any position of their plates in clamping engagement with the work on said plates at least one of the engaged surfaces of each member and said element being so inclined to said plates that each plate is wedged against movement in one of the opposite directions of its to and fro movement while said element maintains the members in clamping engagement with the work.
15. In a sewing machine, the combination of a plane support; two plates movable with their surfaces on said support to and from each other and normally yieldingly urged toward each other; two clamps pivoted on said plates and movable therewith; and a member engaging said clamps and adapted to simultaneously rock said clamps into and maintain them in clamping engagement with work on said plates at least one of the engaged surfaces of each clamp and said member being so inclined to said plates that each plate is wedged against yielding toward the other while said member maintains the clamps in clamping engagement with the work.
